(57) **CLAIM**

The ornamental design for a consumable for an aerosol provision device, as shown and described.

DESCRIPTION

FIG. 1 is a front, top and left side perspective view of a consumable for an aerosol provision device embodying our new design;

FIG. 2 is a front, bottom and right side perspective view thereof;

FIG. 3 is a front plan elevation view thereof;

FIG. 4 is a rear plan elevation view thereof;

FIG. 5 is a left side elevation view thereof;

FIG. 6 is a right side elevation view thereof;

FIG. 7 is a top view thereof;

FIG. 8 is a bottom view thereof; and,

FIG. 9 is a perspective view of the consumable for an aerosol provision device shown in an environment of use.

The broken lines illustrate portions of the consumable for an aerosol provision device that form no part of the claimed design. The additional broken lines in FIG. 9 illustrate environmental subject matter only that forms no part of the claimed design.

1 Claim, 7 Drawing Sheets
